UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

SHORT-TIME-LIMIT SWITCH.

Application filed May 17, 1917. Serial No. 169,227.

To all whom it may concern:

Be it known that I, GEORGE A. BURNHAM, a citizen of the United States, residing at Saugus, in the county of Essex and State of 5 Massachusetts, have invented an Improvement in Short-Time-Limit Switches, of which the following is a specification.

My invention relates to that class of electric switches employed for the control and 10 protection of induction motors, and has particular reference to that type adapted to be actuated to interrupt the circuit upon the occurrence of an overload or upon the temporary cessation of energy in the line.

15 In the operation of induction motors of small powers, it is customary to dispense with the usual starting transformer or compensator and to connect the motor directly to the line and to provide trip coils in circuit with the motor to cause the switch to 20 open upon a harmful overload.

25 In connection with the trip coils, it is customary and highly desirable to employ some form of time limit element, to retard the action of the coils in causing the opening of the switch. Momentary overloads, even though quite severe, will not injure the motor and it is an annoyance and a cause of a loss in production that is of 30 importance in the commercial use of the motors, to be obliged to restart the motor after a momentary harmless overload. Consequently, it is customary to employ a "long time" element in connection with the trip 35 coils of the switch, or an element that will retard the action of the trip coils in causing the opening of the switch for a comparatively long time under a heavy overload. With such a long time element associated 40 with the trip coils of the switch, the current required for the starting of the motor does not energize the coils for a sufficient period of time to cause the opening of the switch.

45 It is also customary to associate with the motor switch what is commonly known as a no-voltage release, the purpose of which is to cause the opening of the switch upon cessation of motor voltage from some cause not brought about by the opening of the 50 motor controlling switch. The no-voltage release consists of a coil connected across the line, the armature of which is adapted to be released upon de-energization of the coil, and, by its release, to cause the opening of 55 the switch.

The no-voltage release serves to prevent the motor from being unknowingly restarted upon re-energization of the line and thus prevents possible damage to the machine to which it is connected or to the material being worked upon by the machine. 60

An object of my invention is to incorporate, in a switch for the control of motors, a single electrically-operated device that will serve to protect the motor against a dangerous overload; that will prevent the restarting of the motor upon its stopping due to a temporary de-energization of the motor not caused by the opening of the motor control switch; and that will permit the motor 65 to be started without operating to open the switch. 70

A further object of my invention is the novel method of operating induction motors by which the motor is disconnected from the 75 circuit due to failure of the electric supply.

When an induction motor has been stopped because of an accidental loss of energy in the line, and not because of the opening of the motor control switch, and this energy is subsequently supplied to the line, with the usual type of motor control switch in its running position, a great rush of current flows through the motor, which continues until the motor has attained normal speed. The trip coils, with their time limit elements, are designed not to be effectively operated by this current, and the separate no-voltage release is depended upon to cause the opening of the switch upon the 80 cessation of line energy. I, however, make use of this temporary large excess of current occasioned by the re-energization of the lines with the motor connected across the line to cause the effective energization of 85 my electrically operated protective device to cause the opening of the switch before the motor has been sufficiently energized to rotate and thus incorporate, in one device, the function of an overload trip coil and 90 the function of a no-voltage release, while also retaining all the features of a time limit opening means, and the means by which I accomplish this desirable and heretofore unattained result is in the peculiar 95 design of the time limit element associated with the overload trip coil. 100

A further object is generally to improve the construction and operation of an electric switch. 110

Certain features of this invention are disclosed in my Patent No. 1,399,460, dated December 6, 1921.

Fig. 1 is a transverse section of a switch embodying my invention.

Fig. 2 is a diagram of the circuit connections.

Fig. 3 is a typical time-current curve of an induction motor.

10 Fig. 4 is a section along line 4—4 of Fig. 1.

Fig. 5 is a detail of the operating mechanism illustrating the relative position of the parts thereof in the open position of the switch.

15 Fig. 6 is a detail similar to Fig. 5 and illustrating the position of the mechanism with the switch in starting position.

Fig. 7 is a detail similar to Fig. 5 and illustrating the position of the mechanism 20 with the switch in running position.

As here shown, an embodiment of my invention is incorporated in the double-throw switch shown in Fig. 1 and described in greater detail and claimed in my Patent No. 25 1,399,460, dated December 6, 1921, in which the base 10 supports the two sets of contacts 11 and 12 between which are disposed the movable set of contacts 13 supported by flexible spring conductors 14, the position 30 of which is controlled by a rod 15 connected by an insulated block 16 to the spring conductors 14 and to an arm of a bell crank 17. A second arm of the bell crank 17 is connected to the operating handle 18 by a link 35 19. An arm 20, associated with handle 18 carries a pin 21 that operates in a slot 22, having a recess 23 in link 19 and said pin is under the control of latch 24 pivoted at 24^a to said link 19. This form of connection be- 40 tween the operating handle 18 and the bell crank lever 17 forms means whereby the movable switch contacts may be moved into open position independently of the operating handle upon the operation of the tripping mechanism, as is more fully described in 45 the above mentioned patent.

In the neutral or switch-open position of the mechanism, Figs. 1 and 5, the pin 21 of the operating handle 18 is or may be in 50 some mid-position in the slot 22 in the link 19 and is free from positive connection with said link and consequently with the operating mechanism. When the handle is operated to move the switch to starting position, the pin 21 is moved to the left, Fig. 5, in the slot 22 and fits within the recess 23 of said slot, the link 19 dropping downward and the latch 24 being moved away from the recess by said pin, for this purpose. The 55 pin 21 is then held releasingly by the latch in said recess and in operative engagement with said link and further movement of the pin serves to move said link, and the remainder of the switch mechanism associated 60 therewith, to the starting position of the

switch. A movement of the operating handle and the pin 21 in the reverse direction effects the movement of the operating mechanism into a running position indicated in Fig. 7. Upon an overload, the pin 35 is 70 actuated by the trip coils 26 to raise the latch 24 and move it from beneath the pin 21, and also raise the link 19 to clear said pin, and the switch consequently moves to open or neutral position as indicated in 75 Figs. 1 and 5.

Depending from base 10 is a casing 25 adapted to contain oil. Depending also from base 10, and arranged within the casing 25, are two trip coils 26 with their cores 27 slid- 80 able in tubes 28 and normally maintained against the adjustable stops 29, the position of which serves to determine the value of overload at which the cores will be effectively attracted to operate to cause the opening of the switch. Retarding disks 30 are secured to the lower ends of cores 27 by means of screws 31, the tubes 28 being provided with slots 32 to provide for the free movement of cores 27 with the attached 90 disks 30, and certain of screws 31 are made with extensions 33 to engage with the enlarged portion 34 of a latch operating pin 35 which projects through base 10 and terminates in close proximity with the under 95 side of latch 23.

Disks 30, in combination with the oil in casing 25, form a time limit element for trip coils 26, the retarding action of which can be varied by varying the shape and dimensions of the disks 30. 100

A diagram of connections between a three-phase line, switch and motor is shown in Fig. 2, in which the line wires 36 are connected to the movable switch members 13 105 disposed between the "starting" contacts 11 and "running" contact 12. Starting contacts 11 are directly connected to motor M by conductors 37 while two of running contacts 12 are connected to motor M through 110 the trip coils 26.

In the operation of the switch, the contacts 13 are first brought into engagement with starting contacts 11. A large excess of current immediately flows through the 115 motor as indicated at *a* in Fig. 3. This current continues to flow, with decreasing strength as the motor increases in speed until a point *b* on the time current curve is reached, at which point both the speed and current have reached normal values. At this point, the movable contacts are shifted from starting to running position. During the time the movable contacts 13 are being moved from stationary contacts 11 to 12, 120 there is no current flowing through the motor, this drop in current being indicated by point *c* in the curve. Due to this momentary loss of energy, the motor speed decreases and when the connection with the line is again 125 130

made through the running side of the switch, a momentary second rush of current occurs as indicated by d on the curve, during which rush of current the speed is again brought up to normal and the current drops to some normal value e .

This second current peak exists for but a short time, say in the neighborhood of two one-hundredths of a second, compared with 10 the duration of flow of the excessive starting current and its value is rarely more than twice normal current flow, while the starting current reaches a value of from five to six times normal current flow.

15 It is evident that the time limit device must so restrain the action of the core of the trip coil that the switch will not be caused to move to open position by the excess current flow occasioned by the movement 20 of the switch from its starting to running position as otherwise the switch could never be maintained in running position long enough for the motor to attain its normal speed, and it is further evident, to 25 prevent the motor from accidental starting, after it has stopped from loss of line energy, with the switch in running position, or in other words to perform the functions of a no-voltage release, that the time limit element 30 must have such a limited delayed action that the switch will be caused to move to open position, upon the re-energization of the line and the consequent excessive current flow through the motor, before the motor 35 has had time to appreciably rotate.

With these conditions fulfilled, the usual overload trip coil, associated with my invention, will perform its own functions as well as those of the no-voltage release, and also 40 give satisfactory delayed action upon overloads.

In the operation of the overload coils having the requisite time limit element, upon the de-energization of the line, the motor 45 ceases to revolve and the switch remains in closed running position, during the period of line de-energization. Upon the re-energization of the line, a heavy starting current immediately flows through the motor and 50 through the overload coils. Due to the short time element, the trip coils are permitted to operate to open the switch before the motor has had time to appreciably revolve. The motor is thereby prevented from operation, 55 and motor and line are protected against injury due to the heavy current flow permitted by a previous cessation of line energization, upon the beginning of the heavy current flow, just as effectively and safely 60 as though the subsequent heavy current flow had been prevented by the opening of the line immediately upon the cessation of line energization.

I claim:

65 1. An induction motor starting and con-

trolling device including an electric switch having starting and running positions, an operating handle movable between starting and running positions and arranged to be held in running position to hold the switch 70 in running position and operating mechanism releasably connecting the handle with the switch, and overload tripping means arranged to break the connection between the operating mechanism and handle and effect 75 the opening of the switch from running position independently of movement of the handle from running position, said switch arranged to be moved to starting position 80 to connect the motor directly to the line for starting and exclude said tripping means, and arranged to be moved from starting to running position and momentarily interrupt the motor circuit and reconnect the motor to the line through said tripping means, 85 said tripping means having retarding means associated with it arranged to hold the tripping means against operative movement due to the momentary overload resulting when the motor circuit is re-established on the 90 running side of the switch and to operate substantially instantly to trip the switch upon an overload having characteristics substantially exceeding those of the aforesaid 95 momentary overload.

2. An induction motor starting and controlling device including an electric switch having starting and running positions, an operating handle movable between starting and running positions and arranged to be 100 held in running position to hold the switch in running position and operating mechanism releasably connecting the handle with the switch, and overload tripping means associated with the running position of the 105 switch arranged to break the connection between the operating mechanism and handle and effect the movement of the switch to open position independently of movement of the handle from running position, said 110 tripping means having retarding means associated with it arranged to hold the tripping means against effective operation due to the momentary overload resulting when the switch is thrown from starting to running position, and effect its operation to trip the switch upon overloads having characteristics substantially exceeding those of the aforesaid 115 momentary overload.

3. An electric switch comprising a casing 120 adapted to contain oil, stationary and movable switch members immersed in the oil in said casing, operating mechanism arranged releasably to hold the switch closed, and overload switch-tripping means having fluid- 125 governed retarding means associated with it also contained in said casing and immersed in the oil therein.

4. An electric switch comprising a casing 130 adapted to contain oil, stationary and mov-

able switch members immersed in the oil in said casing, operating mechanism arranged releasingly to hold the switch closed, and an overload trip coil disposed within said casing having fluid-governed retarding means immersed in the oil in said casing.

In testimony whereof, I have signed my

name to this specification, in the presence of two subscribing witnesses.

GEORGE A. BURNHAM.
